US0D1103694S

(12) **United States Design Patent** (10) **Patent No.:** **US D1,103,694 S**
(45) **Date of Patent:** **** Dec. 2, 2025**

(54) **SUPPORT STRUCTURE FOR GRILL**

(71) Applicant: **REVOACE INC. LIMITED**, Hong Kong (CN)

(72) Inventor: **Kiosky Chung**, Taichung (TW)

(**) Term: **15 Years**

(21) Appl. No.: **29/819,772**

(22) Filed: **Dec. 17, 2021**

Related U.S. Application Data

(63) Continuation of application No. 29/811,824, filed on Oct. 18, 2021, now Pat. No. Des. 1,034,040, and a continuation of application No. 29/811,821, filed on Oct. 18, 2021, now Pat. No. Des. 1,034,039.

CLAIM

The ornamental design for a support structure for grill as shown and described.

DESCRIPTION

FIG. 1 is a front perspective view of a support structure for grill, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof, shown in collapsed condition.

The broken lines shown in FIGS. 1-8 illustrate portions of the support structure for a grill and form no part of the claimed design.

1 Claim, 8 Drawing Sheets
